(57) **CLAIM**

The ornamental design for a multimedia terminal having transitional graphical user interface, as shown and described.

DESCRIPTION

FIG. 1 is a front image of a multimedia terminal having transitional graphical user interface showing our new design; FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof;

FIG. 9 is a ninth image thereof;

FIG. 10 is a tenth image thereof;

FIG. 11 is an eleventh image thereof;

FIG. 12 is a twelfth image thereof;

FIG. 13 is a thirteenth image thereof;

FIG. 14 is a fourteenth image thereof; and,

FIG. 15 is a fifteenth image thereof.

The broken lines shown in the drawings are for illustrative purposes only and form no part of the claimed design.

The appearance of the transitional image sequentially transitions between the images shown in FIGS. 1-15. No ornamental aspects are associated with the process or period in which one image transitions to another image.
